UNITED STATES PATENT OFFICE.

ANGELO PICCIONE, OF BUFFALO, NEW YORK.

LATHERING DEVICE.

Application filed January 17, 1922. Serial No. 529,910.

To all whom it may concern:

Be it known that I, ANGELO PICCIONE, a subject of the King of Italy, residing at Buffalo, in the county of Erie and State of New York, have invented new and useful Improvements in Lathering Devices, of which the following is a specification.

This invention relates to lathering devices for use by barbers to produce lather for shaving purposes, and has for its object the provision of a device of this character which permits of easily and conveniently cleaning the cup and brush after each shaving operation and thus render the same more sanitary as well as facilitating the work of the barber.

In the accompanying drawings: Figure 1 is a vertical section of my improved lathering device. Figure 2 is a horizontal section of the same taken on line 3—2, looking downwardly. Figure 3 is a similar view taken on the same line but looking upwardly. Figure 4 is a fragmentary vertical section on line 4—4, Fig. 2. Similar characters of reference indicate corresponding parts throughout the several views.

This lathering device, in its general construction, comprises a cup which may be made of metal or any other suitable material to form a cylindrical upright wall 10 and a bottom one part of which is elevated to constitute a shelf 11 upon which the soap and water may be mixed to form lather and another part being depressed to constitute a bowl or fount 12 in which water is held in which the bristles of the brush are dipped preparatory to mixing the same with the soap for making lather.

The elevated part of the bottom contains an outlet 13 for the discharge of water and soap suds from the cup into the delivery nipple 14 arranged below the outlet and adapted to be connected at its lower end with a drain pipe leading to a sewer or waste pipe. This outlet is controlled by a vertically movable flush valve 50 which in its lowered position engages a seat around the upper edge of the outlet and closes the latter but which may be raised to uncover the outlet and permit the contents of the cup to be washed out and discharged through the outlet. The water for thus flushing or washing out the cup is preferably delivered into the same by a spray ring 15 arranged around the inner side of the cup adjacent to the

top thereof and connected by a valve 16 with a water supply pipe 17 on the outer side of the cup and provided on its underside with an annular row of perforations 18 through 60 which a shower of water in the form of an annular stream is delivered downwardly along the inner side of the cup.

Immediately below the spray ring a single stream faucet 19 is arranged to which water 65 may be supplied from the supply pipe 17 by opening a valve 20 on the exterior of the cup, thereby enabling a barber to wet his hand for rubbing the face of a customer preparatory to finishing the shaving operation in 70 the customary manner.

While the cup is being flushed out the upper end of the same is preferably closed by a cover 21 to prevent splashing outside, this cover being preferably pivotally connected on one side of its edge to the upper edge of the cup by a hinge 22, so that the cover can be swung downwardly over the upper end of the cup for closing the same or upwardly for uncovering the cup when 80 the same is required for making lather. Means are preferably provided for holding the cover in its closed position, which means may consist of a catch 23 pivoted on the cup and adapted to be yieldingly held in engagement with the upper side of the edge portion of the cover opposite its hinge by a spring 24 interposed between the cup and catch.

The opening and closing of the flush valve 90 in the bottom of the cup is preferably effected automatically upon closing and opening the cup. The preferred means for this purpose shown in the drawings comprise a vertically-swinging rock lever 25 connected 95 at its inner end with a stem 26 projecting downwardly from the lower side of the flush valve, and an upright vertically reciprocating shifting rod 27 connected at its lower end with the outer end of the rock lever and 100 adapted to be engaged at its upper end by the cover when the latter is closed, and springs 28, 29 operating to turn the lever in the direction for closing the flush valve. When the cover is open the springs 28, 29 105 close the flush valve and thus retain the soap suds or foam in the cup for use by the barber on the face of the customer, but upon closing the cover the flush valve is opened automatically, thereby permitting the water 110 from the spray pipe to wash or rinse the contents of the cup into the drain.

The lever is arranged in a horizontal channel 30 extending from the side of the cup to the discharge nipple and is pivoted between its outer and inner ends to a bracket 31 depending from the top of this channel. In order to render this channel accessible for inspection, adjustment or repairing the parts within the same, the bottom of the cup is constructed in sections, one section 32 being preferably fixed and forming a permanent part of the bottom and connected with the side walls and bottom of the channel, and the other section 33 forming the top of the channel and detachably connected with the fixed section of the cup bottom by screws 34. The flush outlet of the cup is preferably formed partly on the fixed and partly in the detachable section of the cup bottom. The shifting rod is preferably arranged on the inner side of the cup and guided in lugs 35 projecting therefrom. The spring 28 has a pushing effect and the spring 29 a pulling effect, but if desired any other suitable spring arrangement may be employed.

The brush whereby the lather is formed in the cup and applied to the face of the customer is preferably suspended on the inner side of the cup when not in use for which purpose a clasp 36 is arranged on the inner side of the cup above the water fount, so that upon engaging the handle 37 of the brush with this clasp, the bristles 38 on the lower end thereof are arranged in the fount, as shown in Figs. 1 and 2. While the brush is in this position, the same may be washed by streams of water issuing from one or more jets 39 projecting outwardly from the inner side of the fount and connected by a valve 40 with the main water supply pipe so that the bristles of the brush may be washed and rinsed when desired while the same is enclosed.

This lathering device is very compact in construction, it has no parts which are likely to get out of order and the same provides a very convenient means for expeditiously producing lather for shaving a customer and then cleaning out the cup for promoting sanitation.

I claim as my invention:

1. A lathering device, comprising a cup provided in its bottom with an outlet, a vertically movable valve adapted to move upwardly to open said outlet and downwardly to close the same, a cover pivoted to the upper end of said cup, a lever connected

with said valve and an upright rod connected at its lower end with said lever and adapted to be engaged at its upper end by 60 said cover.

2. A lathering device, comprising a cup provided in its bottom with an outlet, a nipple arranged below said outlet, and a horizontal channel leading from the side of the cup to said nipple, a valve movable vertically toward and from said outlet, a rock lever arranged in said channel connected at its inner end with said valve, an upright shifting rod guided on the inner side of said cup and connected at its lower end with said lever, a spring for turning said lever in the direction for closing said valve and raising said rod, and a cover pivoted to the upper end of said cup and adapted when moved downwardly into its closed position to engage the upper end of said rod and depress the same for opening said valve.

3. A lathering device, comprising a cup provided at its bottom with an outlet, a nipple arranged below said outlet, and a horizontal channel leading from the side of the cup to said nipple, a valve movable vertically toward and from said outlet, a rock lever arranged in said channel connected at its inner end with said valve, an upright shifting rod guided on the inner side of said cup and connected at its lower end with said lever, a spring for turning said lever in the direction for closing said valve and raising said rod, and a cover pivoted to the upper end of said cup and adapted when moved downwardly into its closed position to engage the upper end of said rod and depress the same for opening said valve, the bottom of said cup having a fixed section connected with the side walls of said channel, and a removable section which forms the top of said channel and is detachably connected with said fixed section.

4. A lathering device, comprising a cup having a bottom one part of which is elevated to receive soap and a part which is depressed to form a water fount, and an outlet in said elevated part of the bottom, means for supporting a brush on the inner side of said cup with its bristles projecting downwardly into said fount, and valve controlled water delivery jets projecting outwardly from the inner part of said fount toward the inner side of the cup and adapted to deliver water against the bristles of the brush.

ANGELO PICCIONE.
